UNITED STATES PATENT OFFICE

2,506,706

INCANDESCENT MANTLE FOR LIGHTING
AND HEATING APPLIANCES

William George Colle, London, England, assignor
to The Tilley Lamp Company Limited, London,
England, a company of Great Britain

Application September 9, 1948, Serial No. 48,418
In Great Britain August 11, 1948

6 Claims. (Cl. 67—98)

1

This invention relates to incandescent mantles for lighting and heating appliances and of the kind known as soft mantles, that is to say mantles woven in tubular form from artificial silk, vegetable fibres, asbestos, synthetic thread or the like impregnated with one or more substances to render it incandescent when heated by the flame from a burner to which it is attached at one or more points so that the flame is directed into the tubular mantle.

For convenience the term "burner" will be used herein to denote that part of the apparatus to which the tubular mantle is attached and from which the burning gases are emitted to render the mantle incandescent while the term "incandescent substance" will be used to denote the substance or substances which the soft tubular mantle contains to render it incandescent when heated by the burner whether such substances are in their final form before the mantle is brought into use or are converted into the appropriate substance or substances by the mantle being brought into use. The term "resilient" will be used to describe a member which can be deformed by moderate manual pressure and which will return to its original shape promptly when this pressure ceases to be exerted.

The invention is particularly applicable to soft mantles formed by weaving a continuous tube which is cut into lengths to form the individual mantles, where either both ends are adapted to be secured to the burner, or one end only is adapted to be secured to the burner while the other end is either closed or restricted in diameter by means of a draw thread or cord, but it is to be understood that the invention may also be applied to soft tubular mantles of the kind in which one end of the mantle is substantially closed in the process of weaving.

Soft tubular mantles as at present made are provided with a draw thread or cord at one or both ends extending circumferentially around and threaded in and out through the ends of the woven tube and tied, or with provision for tying. The draw thread at the end which is to be secured to the burner gives to this end of the tube an effective diameter such that it can be forced over the end of the burner, usually into a circumferential groove therein. This operation, which is necessary whenever a mantle has to be

2

replaced is not easy to perform satisfactorily, with the result that the mantle is often damaged or incorrectly located on the end of the burner or is twisted or otherwise deformed. The replacement of a mantle thus not only takes appreciable time but is frequently wrongly carried out, to the detriment of the life of the mantle and the light given out.

The present invention has for its object to provide an improved soft tubular mantle assembly which will enable replacement of a mantle to be quickly, easily and correctly performed and at the same time will be simple to manufacture in quantity.

15. A soft tubular incandescent mantle assembly according to the present invention comprises a soft woven tubular element including the incandescent substance or substances and a resilient ring lying within one end of the tubular element and to which that end of the tubular element is secured by a surrounding cord or band having sufficient resilience to permit the ring to be sprung on to the end of the burner. Conveniently the surrounding member is in the form of a securing thread or cord tied around the tubular element and the ring, the thread or cord having sufficient resilience to permit the required expansion of the ring when it is sprung on to the end of a burner. Thus the ring is conveniently formed with an external circumferential groove or recess, formed for example by providing circumferential flanges at its two edges, into which groove the thread or cord presses the part of the tubular element which it surrounds.

In any case the end of the tubular element which is secured to the ring is preferably turned inwards to provide two concentric layers, the ring lying within the inner layer with the cord or band lying between the two layers. This may be effected by first placing the ring inside one end of the tubular element, securing the securing thread or cord around it and then turning the tubular element inside out by pushing the ring through it.

The form of the ring may vary considerably but in a preferred form it is made from a strip of sheet metal the edges of which are turned over to form flanges while its ends are formed so as to overlap and interengage, when the strip

has been bent into the form of a ring with the flanges projecting outwardly, in a manner permitting limited sliding movement between the overlapping ends of the strip and hence allowing for the required limited expansion and construction of the ring. For example one end of the strip may be provided with a tongue which projects over the part of the other end of the strip between the flanges and is of such width that its edges lie and can slide under the flanges. Thus, the tongue is slightly overlapped by the flanges so that it can slide longitudinally relatively thereto but is held in close proximity to the part of the strip between the flanges over which it lies.

The invention may be carried into practice in various ways but one way of carrying the invention into practice is illustrated by way of example in the accompanying drawings, in which

Figure 1 shows in perspective the two parts of the mantle assembly before they are united,

Figure 2 shows the ring at an intermediate point in its formation,

Figure 3 shows the two parts of the assembly in their partly assembled state,

Figure 4 is a sectional side elevation showing the mantle assembly applied to a burner, and

Figure 5 is a perspective view of the mantle assembly in position on a burner before lighting.

The mantle assembly is made up from a tubular element A which is woven from artificial silk, vegetable fibres, asbestos, synthetic thread or the like impregnated with one or more suitable incandescent substances in the usual manner, and has a draw string A¹ extending around and threaded in and out through one end as shown, and a resilient metal ring B.

The ring B is formed from a strip of metal of appropriate length the edges of which are turned over as shown at B¹ in Figure 2 to form flanges, while one end, in the form of a tongue B², projects beyond the flanged part. The strip of metal, which thus has the form shown in Figure 2, is then bent into the form of a ring as shown in Figure 1 with the edges of the tongue B² slipped under the inturned edges of the strip constituting the flanges at the opposite end of the strip. The tongue B² is free to slide longitudinally beneath the flanges B¹ so as to permit small variations in the diameter of the ring and the bending of the strip into a ring is so performed that the resilience of the ring B always tends to close it to its smallest diameter.

In assembling the tubular element A and the ring B, the ring B is placed within the end of the tubular element A remote from the draw string A¹, and a securing cord C is tied tightly around the part of the tubular element around the ring so as to secure this end of the tubular element to the ring as shown in Figure 3. The securing cord may either be passed once or more around the ring and knotted as shown or may be formed into a clove hitch around the ring.

In any case after the end of the tubular element has been secured to the ring as shown in full lines in Figure 3 the tubular element is turned inside out by passing the end secured to the ring through the tubular element so that the end of the tubular element secured to the ring becomes folded over on itself as indicated in dotted lines at A² in Figure 3 and Figure 4 with the securing cord C lying between the two folds.

The end of the tubular element A remote from the ring B may then be drawn in by the draw thread A¹ to a suitable diameter to fit around

the part of a burner or like member which it is to engage or may be left as shown in Figure 3 in readiness to be drawn in when applied to a burner. Generally it will be preferred to draw this end in to an appropriate diameter so that when fitted to a burner it only has to be pushed over the appropriate part.

The improved mantle assembly formed in the manner described above is intended for application to a burner of the known type shown in Figures 4 and 5 comprising a mixing chamber D to which vaporised fuel is delivered through a passage D¹ having an external circumferential groove D², while air is drawn in through passages D³, and an annular nozzle D⁴ having a ring of burner passages D⁵, and an external annular groove D⁶. In applying a mantle assembly as described above to such a burner the ring B is pressed upwards over the end of the nozzle until it springs into the groove D⁶, the resilience of the ring B and of the securing cord C permitting the ring to expand to the required extent and then causing it to contract into the groove D⁶ so as to be securely mounted on the burner. The lower end of the tubular element A is then pressed over the lower end of the passage D¹ into a circumferential groove D² therein so that the mantle assembly occupies the position shown in Figures 4 and 5.

When the mantle is lit it shrinks into its final form in known manner.

Usually in constructions of burner of the type shown the vaporised fuel will be delivered to the burner through a tube passing up through the passage D¹ and provided with a central valve, but since the construction of burner forms no part of the present invention, it will not be further described.

What I claim as my invention and desire to secure by Letters Patent is:

1. A soft tubular incandescent mantle assembly comprising a soft woven tubular element containing the incandescent material, a diametrically expansible resilient ring lying within one end of the tubular element, and a securing cord surrounding the end portion of the tubular element around the ring and serving to secure such end portion to the ring, the cord permitting the ring to be manually expanded so that it can be sprung onto a burner.

2. A soft tubular incandescent mantle assembly as claimed in claim 1, in which the end of the tubular element surrounding the resilient ring is turned inwards so as to provide a circumferential fold and the securing cord lies between the two layers of the fold.

3. A soft tubular incandescent mantle assembly as claimed in claim 2, in which the resilient ring is formed from a strip of material bent into cylindrical form with its two ends overlapping and interengaging and capable of sliding circumferentially to a limited extent relatively to one another without becoming disengaged from one another.

4. A soft tubular incandescent mantle assembly as claimed in claim 3 in which the ring is formed from a strip of sheet metal the edges of which are turned over to form two shallow outwardly extending flanges between which the securing cord lies, a tongue projecting from the part of one end of the strip lying between the flanges over the part of the other end of the strip between the flanges with the edges of the tongue lying and slidable longitudinally beneath such flanges.

5. A soft tubular incandescent mantle assembly as claimed in claim 1, in which the resilient ring is formed from a strip of material bent into cylindrical form and the two ends of said strip overlap one another and interengage and can slide circumferentially to a limited extent relatively to one another without becoming disengaged from one another.

6. A soft tubular incandescent mantle assembly as claimed in claim 5, in which the ring is formed from a strip of sheet metal the edges of which are turned over to form two shallow outwardly extending flanges between which the securing cord lies, a tongue projecting from the part of one end of the strip lying between the flanges over the part of the other end of the strip between the flanges with the edges of the

tongue lying and slidably longitudinally beneath such flanges.
